UNITED STATES PATENT OFFICE.

JOHN HERBERT HAMILTON, OF NORTH ANDOVER, MASSACHUSETTS.

MEANS FOR TENTERING FABRICS.

Application filed March 23, 1927. Serial No. 177,575.

My invention relates to a machine for tentering fabrics; the machine employed, belonging to that class having travelling chains provided with clamps that travel 5 along guide-rails, for the purpose of stretching, smoothing and drying continuous webs of, say, cotton cloth.

The ultimate object of both features of my invention is to obtain, at substantially the 10 same cost, a large increase in the production of tentered fabrics, over that now attained with the best known resources.

I have found that when my method is carried out by my machine, the productive capacity of the latter is much greater than that 15 of any tentering machine known to me; in fact, as between mine and the most efficient of those in the prior art, operating at the same speed and for the same period of time, 20 the quantity of cloth successfully tentered by my machine may be said to be about twice that tentered by the best of those now in use.

Further, be it noted that the modern 25 tentering machine requires, as does mine, the attention of two operatives. If, as often happens, the business of a mill absolutely requires that more cloth be tentered than can be, by one machine, in one day, then for 30 extra or night work, these men must be paid larger and additional wages.

If the quantity to be tentered is beyond the capacity of one machine, then a second machine must be purchased, set up and operated 35 by two operatives. This means a doubling of cost for machinery, for operating expenses, and of floor space for tentering.

Now by reason of my method and of my apparatus, I overcome these objections and 40 obtain,

- (1) Greatly increased production;
- (2) A saving in cost for machinery;
- (3) Saving in number of operatives employed;

- (4) Saving in cost of over-time work;
- (5) Saving in floor space in mill;

All of which savings are of great value to the textile manufacturers, both the large, and especially the smaller.

50 My method resides in any tentering process whereby two or more webs of fabric, with an intervening air space between the adjacent webs, may be simultaneously and uniformly successively fed, conveyed, 55 stretched and delivered; and my machine,

invented by me to carry out my method, comprises, broadly, a pair of endless conveyor chains, means for operating them, and a plurality of superimposed clamps integral with each link of the conveyor, and 60 means seasonably and simultaneously to open and to close, for the reception, the holding, and the release of the selvage edges of said plurality of webs of fabric moving in parallel separate planes. 65

The accompanying drawings illustrate the principles of my inventions, and the best mode now known to me of embodying them in operative structures.

Fig. 1 is a diagrammatic view, in elevation, of the apparatus, and machinery making use of my new method of tentering; the chains and the gripping means being omitted to avoid confusion. 70

Fig. 2 is a plan of the tentering machine; 75 its chains and gripping means being indicated by dash and dot lines.

Fig. 3 is an enlarged cross-sectional view on line 3—3, Fig. 2.

Fig. 4 is a right side elevation of Fig. 3, 80 partially in section.

Fig. 5 is a partial plan view of Fig. 4.

Fig. 6 is an end elevation of entering 85 end of said tentering machine shown in Fig. 2; some of its parts being omitted for the sake of clearness.

That one may gather a general idea of the features of my invention, reference may be made to Figs. 1 and 2; Fig. 1 showing from beginning to end, my means using my 90 method of tentering a plurality of webs of fabric, uniformly and simultaneously.

Two trucks A, B, each having a damp piece of fabric C, D that has been extended from washers, are placed under two overhead racks, E, F made up of a series of tension bars, G, H. One web C is led through rack E, and the other D, through rack F, each web, respectively, being directed into the entering end of the machine by any 100 well known automatic, compressed-air cloth guiders I, J; and after passing under their respective tension rolls K, L both webs C, D are seasonably simultaneously, but separately, seized at their respective selvages, 105 as will be described hereinafter, by a plurality of superimposed clamps 2, 2', Figs. 2 and 6, mounted on the links 3 of the chains 4, 4'; and are conveyed and stretched in the usual manner, the two webs C, D, moving 110

through the machine in separate parallel horizontal planes with an air space between them. Upon the arrival of the webs at the delivery end of the machine, the clamps are 5 simultaneously opened, as will later appear, and each web is delivered to any suitable mechanism M which, for example, forms them into rolls C', D' .

The basis of this tentering machine is 10 old; but, due to the features of my invention, it has become a new, and is a vastly more productive machine than it was before it embraced these features.

As in other machines, upon supports O , 15 Fig. 1, there are two longitudinal guide-rails P each supporting an endless chain $4, 4'$, travelling in stretching guide-ways Q , and driven around idle sprockets, R^2, R^3 , by sprocket wheels R, R' , Fig. 2 at the delivery 20 end of the machine, fixed to shafts S receiving their power from bevel gears operated by a driving shaft T receiving its power from a suitable source.

The guide-rails are of the usual construction, and, by use of hand wheels V, U and cooperating mechanisms, may be moved to give any desired width to the tentering machine.

In order that I may simultaneously and 30 uniformly tenter two or more webs of fabric, I provide integral with, and projecting laterally from, each link 3 , Figs. 3, 4, and 5, of each endless chain, as 4 , Fig. 2, a standard 5 for the reception of a plurality of 35 clamps $2, 2'$ designed to be seasonably opened and closed by cams and gravity, to receive and to grip the selvage of a plurality of webs C, D of fabric.

The standard 5 is E-shaped in vertical 40 section, the middle and lower arms 6, 7 forming bases for clamp-plates $6', 7'$ of the clamps $2, 2'$; while the upper and the middle arms $8, 7$ support pins $9, 9'$ upon which swing gravity operated jaws $10, 10'$ that, 45 when free, fall upon the fixed clamp-plates, $6', 7'$ and grip the selvages that may lie upon the clamp-plates.

Upon the front of each movable jaw as 50 10, is a boss 11 to be engaged in a manner later to be explained, for raising each jaw while in the rear mid portion of the movable clamp-plate, is a slot 12, Fig. 5, in which one leg 13 of an L-shaped controller operatively connected to the jaw and pivoted at 55 14 in the standard, is free to be moved by the jaw, to raise the jaw and permit the selvage of the fabric to be positioned thereunder, see Fig. 6, upon entering the machine, or by gravity, when the boss on the 60 jaw is not engaged by a cam surface.

To sustain the standard 5 and clamps $2, 2'$, Fig. 3, in a fixed plane in relation to the machine frame, the guide-way Q in the top surface of each guide-rail, to receive each 65 link 3 of the chain, is, in cross-section, that

of the link. At the back of the link, projecting rearwardly, is an integral guide member 15, Figs. 3, 5, and 6, in sliding engagement with a lock rail 16 that resists any tendency on the part of the conveyor 70 link, to turn, due to the pull of the stretching fabrics away from the clamps. To resists this tendency still further, a supporting rail 17 is fixed to the inside of the guide-rails of the machine.

Seasonably to open, simultaneously and momentariaiy, the normally closed clamps $2, 2'$ on each link of the chain, to receive the selvage of the fabric, at the feed end of the machine, see Fig. 6, and release it at the delivery end, there are fixed to the machine frame four groups $18, 18', 19, 19'$, Figs. 1, 2 and 6 of cam surfaces, each group, as 18 , Figs. 1 and 6, comprising a plurality of semi-circular cam surfaces $20, 20'$, each 85 group, respectively, having a centre in common with that of its sprocket wheel, and adapted to engage the bosses 11, 11' on the superimposed jaws $10, 10'$ of the clamps $2, 2'$.

That the webs of fabric may move from the cloth guides I, J , Fig. 1, into the positions required, Figs. 1 and 6, to be seized by the clamps, a plurality of delivery plates $22, 22'$, Fig. 6, is provided which deliver 90 the advancing selvages $23, 23'$ into the open spaces between the clamp-plate and jaw of each clamp, brought about by said opening cams.

I will now describe the operation of the 100 features of my invention.

By means of the hand wheels U, V , Fig. 2, shafts and bevel gears shown, the longitudinal guide-rails P, P and endless conveyor chains $4, 4'$ are moved into the position appearing in Fig. 2, the dot and dash lines indicating the endless chain links 3 , each with its two superimposed clamps $2, 2'$, Fig. 3, all properly arranged to tenter two webs of fabric C, D , simultaneously and uniformly, said webs being contained, as already stated, in the two trucks A, B , in Fig. 1.

Power from a suitable source being applied to the machine through the large gear W , Fig. 2, shaft T , bevel gears, shafts S and driving sprockets R, R' , indicated in Fig. 1, the two endless chains $4, 4'$, move along their respective guide-ways Q , in the guide-rails P, P and about the driving and the idle 110 sprocket wheels R, R', R^2, R^3 , as indicated by the arrows in Fig. 2.

The machine being in motion, the web of fabric C , Fig. 1, from truck A having been drawn over the bars G of the rack E , and through the cloth guides I , as has, likewise, the web D from truck B , over its bars H and through its cloth guides J , a narrow threading tape is next attached to the free end of each web, drawn under their respective feed 120

rolls K, L, over the delivery plates 22, Fig. 2, through the machine, and over tension bars, to the mechanism M for forming the tentered pieces of fabric C, D, for example, into rolls 5 C', D'.

As this mechanism M begins winding the two separate tapes, the free ends of the webs of fabric C, D, approach and move over the delivery plates 22; their respective selvages 10 23, 23' being guided by hand into their respective open spaces between the clamp-plate 6', 7' and jaws 10, 10', Figs. 3 and 6, of the clamp 2, 2', and held open by the engagement of the bosses 11, 11' of the jaws 15 with the cam plates 20, 20' from which said bosses are about to become disengaged.

At the moment of disengagement, the jaws 10, 10' and legs 13, 13' of the controllers, fall, but while the latter fall upon 20 the selvages 23, 23', they also hold the jaws out of gripping engagement with the selvages. As the chains 4, 4', clamps 2, 2', and fabrics C, D, move forward, the chains and clamps move apart, and in controllers 25 finally slip off the edges of the selvage, drop down into the cavities in the bases, and free the jaws, which at once, with the clamp-plates, bite and securely hold the selvages.

In this way, each portion of the selvage 30 of each of the two webs of cloth, simultaneously enters the machine, is simultaneously seized, and the webs are simultaneously and uniformly stretched in width, as they proceed to the central portion of the machine, 35 where the advancing parts of the endless chains with the gripped selvages of the webs, begin and continue to move in parallelism, until their clamps are released by the bosses of the gates engaging the release cams, 19, 40 19'.

From the machine, these two separate webs C, D, pass over suitable bars, and are wound up into rolls C', D', upon their respective winding rollers ready for the next 45 operation, if any, to which they are to be subjected.

Having described the method and the means, invented by me, whereby, in the tentering art, there may be obtained

50 (1) Greatly increased production; (2) A saving in cost for machinery; (3) Saving in number of operatives employed; (4) Saving in cost of over-time work; 55 (5) Saving in floor space in mill;

And desiring to protect said means in the broadest manner legally possible.

What I claim is:—

1. In a tentering machine, driving mechanism; a pair of travelling chains moved by 60 said mechanism and both lying in the same horizontal plane; cloth gripping units connected to links of said chain, each unit comprising a plurality of superimposed downward-moving gripping jaws; stretching- 65 guides for holding said gripping units in their respective operating planes; and means for seasonably opening and closing each of said jaws for the purpose of simultaneously and seasonably receiving, seizing 70 and releasing a plurality of moving webs of fabric separate from each other but in parallelism while passing through the machine.

2. In a tentering machine, a pair of continuously-travelling chain conveyors running in the same horizontal plane and mechanism for driving the same, each link of said chains being provided with two independent cloth-gripping units mounted one above 75 the other, each of said units embodying its own gripping-plate and downwardly-moving gripping-devices, and stretching-guides for the chains located under the chains, 80 whereby the one set of chains and stretching-guides serve to uniformly tenter two webs of cloth.

3. In a tentering machine, driving mechanism, a pair of travelling chains moved by 90 said mechanism and both lying in the same horizontal plane, said mechanism embodying chain-carrying wheels whose axes are vertical, cloth-gripping-units mounted on top of the links of said chains, each unit comprising a plurality of superimposed gripping-jaws, 95 and companion clamp-plates, all the clamp-plates having their clamping-faces facing upwardly, stretching-guides for holding said gripping-units in their respective operating planes, and means for seasonably opening 100 and closing each of said jaws for the purpose of simultaneously and seasonably receiving, seizing and releasing a plurality of moving webs of fabric separate from each other but in parallelism while passing through the machine.

In testimony whereof I hereunto affix my signature.

JOHN HERBERT HAMILTON.
